UNITED STATES PATENT OFFICE

2,012,678

STRAP JOINT

William C. Childress, Oak Park, Ill., assignor to
Acme Steel Company, Chicago, Ill., a corpora-
tion of Illinois

Application February 10, 1932, Serial No. 592,052

5 Claims. (Cl. 24—20)

This invention relates to improvements in strap joints and its purpose is to provide improved means for uniting the overlapping ends of a strap or binder such as employed for forming bales, reinforcing boxes or packages, and binding a number of packages together. It has heretofore been the usual commercial practice to unite the ends of metal straps and binders by means of a strap seal such as that described and claimed in the United States patent of Ralph H. Norton, No. 1,260,016, dated March 19, 1918, but, while an efficient joint may be formed by the invention of that patent, it involves the use of a separate sleeve or the like for enclosing the overlapping strap ends so that the operator must manipulate this additional element and keep in stock a supply of sleeves for straps of various widths.

The principal object of the present invention is to provide improved means of and a method for forming a strap joint according to which the overlapping strap ends are united by being deformed to interlock with each other in such a manner that relative transverse and endwise movement of the two strap ends is effectively prevented. A further object of the invention is to provide an improved strap joint in which the overlapping strap ends are rolled or curled at their edges to form longitudinal telescoping beads adapted to prevent relative transverse separation of the strap ends, in combination with transversely extending crimps formed in the strap ends to prevent relative longitudinal separation thereof. Still another object of the invention is to provide an improved strap joint in which the overlapping strap ends are rolled at their edges to provide parts adapted to prevent relative transverse separation in combination with interlocking shoulders formed by crimping the overlapped parts of the strap and by transversely shearing marginal portions of the strap ends. A further object of the invention is to provide an improved strap joint in which the marginal rolling of the strap ends is combined with two or more series of transverse cuts formed by shearing marginal portions of the strap ends to provide shoulders adapted to prevent relative longitudinal movement of the two ends. Other objects relate to various features of construction and details of the improved method such as will appear more fully hereinafter.

The nature of the invention will be understood from the following specification taken with the accompanying drawing in which the improved

method is explained in connection with three embodiments of the improved joint.

In the drawing,

Figure 1 shows a top plan view of two overlapping strap ends preliminary to the formation of the joint of the present invention;

Fig. 2 shows a top plan view of the overlapping strap ends after having formed therein the improved joint of the present invention;

Fig. 3 shows a side elevation of the joint illustrated in Fig. 2;

Fig. 4 shows a bottom plan view of the improved joint shown in Fig. 2;

Fig. 5 shows an enlarged transverse section taken on the line 5—5 of Fig. 2;

Fig. 6 shows an enlarged transverse section taken on the line 6—6 of Fig. 2;

Fig. 7 shows a bottom plan view of a modified form of joint embodying the principles of the present invention;

Fig. 8 shows a top plan view of a strap joint embodying another modification of the invention; and

Fig. 9 shows an enlarged transverse section taken on the line 9—9 of Fig. 8.

Referring to the form of the invention illustrated in Figs. 1 to 6, inclusive, of the drawing, it will be seen that the invention is applied to the overlapping ends 10 and 11 of a flat steel strap such as is commonly employed as a flexible binder. After overlapping the ends of the strap in this way, marginal portions of the overlapping parts of the strap ends are bent transversely to form two telescoping beads along the edges of the strap ends, but this rolling operation is preferably preceded by shearing the overlapping ends along the lines 12 to form cuts which extend inwardly at right angles to the length of the strap. After forming these cuts 12, the marginal portions of the overlapping strap ends, between the cuts, are rolled downwardly and inwardly to form telescoping beads 10^a and 11^a on the overlapping ends as shown particularly in Fig. 5. The beads on the under strap may be complete beads of substantially circular cross section, as illustrated, while the beads on the uppermost strap may be somewhat less than the complete beads due to their greater circumference. When the marginal portions of the strap ends are rolled in the regions 13, between the cuts 12, the metal at the ends of the beads is turned downwardly and inwardly, at the cuts 12, to form interlocking overlapping shoulders as shown at 14 so that relative endwise movement of the strap ends is thereby prevented.

As a further means of insuring against longitudinal movement of the strap ends, the marginal portion of those parts of the strap on which the beads 10^a and 11^a are formed, are preferably crimped transversely as shown at 15. These crimps are formed by bending the metal of the marginal beaded portions of the strap transversely while maintaining surrounding areas of the strap in their original form. This results in flattening out the beads of the strap at the points where the crimping takes place, as shown at 15^a and the crimps which extend downwardly, transversely to the plane of the strap, create shoulders which prevent relative endwise movement in addition to insuring further against relative transverse separation of the strap ends. Those portions of the strap ends which lie between the beads and between the crimps 15 are retained in their original flat shape as shown at 16.

In Fig. 7 of the drawing there is illustrated a modified form of the invention in which the two strap ends 20 and 21 have marginal portions thereof rolled or bent inwardly to form marginal telescoping beads 22. These beads diminish toward their ends and are curved outwardly as shown at 22^a so that interlocking shoulders are provided for preventing relative endwise movement even though the strap is not sheared transversely at the ends of the beads, as in the form of the invention first described. The bead 22 includes inner and outer beads on the two overlapping strap ends and these have a telescoping engagement with each other along each edge of the strap so that they effectively prevent relative transverse movement of the strap ends in any direction. In addition, the intermediate portions of the beaded parts of the strap ends are crimped transversely as shown at 23, forming crimps similar to the crimps 15 previously described, so that additional interlocking shoulders are thereby provided for preventing separation of the strap ends.

In Figs. 8 and 9 of the drawing there is illustrated still another modification of the invention in which the two strap ends 25 and 26 are overlapped and then, while the strap ends are held in alignment with each other, portions of the strap ends are rolled or bent inwardly and downwardly to form marginal beads 28 which include telescoping beads formed on the two strap ends so that they are located one within the other as shown in Fig. 9 to prevent relative separation of the parts. When these marginal portions of the straps are rolled or bent to form the beads, the portions of the strap at the ends of the beads are bent transversely to form interlocking abutting shoulders as shown at 29 so that relative endwise movement of the strap ends is resisted by these shoulders. In addition, intermediate parts of the strap ends, between the shoulders 29 on the same side of the strap, are transversely sheared along lines 30 and the portions of the metal adjacent the cuts 30 are bent transversely to form down-

wardly deflected lugs 31, thus creating additional interlocking shoulders which prevent relative endwise movement of the strap ends. Two pairs of cuts 30 are preferably provided on each side of the strap ends so that the metal between the cuts may be bent downwardly to form two lugs 31 on each side, but a single cut may be employed with the metal bent downwardly at one side of the cut, or a single pair of cuts 30 may be provided along each side of the strap ends.

Although several forms of the improved strap joint have been illustrated and described in connection with the explanation of certain methods of forming these joints, it will be understood that the invention may be constructed in various embodiments and practiced in various ways within the scope of the appended claims.

I claim:

1. A strap joint comprising overlapping strap ends having spaced cuts extending inwardly from each edge thereof with the marginal portions of the strap ends between each pair of cuts turned inwardly to form telescoping parts, said strap ends having parts of said marginal portions thereof deflected transversely to form interlocking shoulders.

2. A strap joint comprising overlapping strap ends having spaced cuts extending inwardly from each edge thereof with the metal between each pair of cuts turned inwardly to form telescoping parts along each edge of the strap ends, intermediate portions of said turned parts being transversely deflected to form interlocking shoulders.

3. A strap joint comprising overlapping strap ends having edge portions thereof turned inwardly one within the other along each side of the strap ends to form substantially cylindrical telescoping tubular parts, said strap ends having marginal portions of said turned tubular parts transversely deflected to form interlocking shoulders, the portions of said strap ends between said turned tubular portions and said transversely deflected portions being in flat condition.

4. A strap joint comprising overlapping strap ends having edge portions thereof turned inwardly one within the other to form telescoping tubular parts of substantially cylindrical form along each edge of the strap ends, the marginal portions of said turned parts being transversely sheared, the metal adjacent the sheared part being transversely deflected to form interlocking shoulders.

5. A strap joint comprising overlapping strap ends, the metal along a part of each edge of said strap ends being turned inwardly to form telescoping tubular parts of substantially cylindrical form, the turned parts of each edge of said strap being transversely sheared between their ends to form a pair of spaced cuts at each side of the strap ends, the metal between each of said pairs of cuts being transversely deflected to form interlocking shoulders.

WILLIAM C. CHILDRESS.
